United States Patent

Des. 239,420

Patented Apr. 6, 1976

239,420

SOCK

Edward M. Clark, Greensboro, N.C., assignor to Kiddie Tot Hosiery Mills, Inc.

Filed Nov. 6, 1974, Ser. No. 521,350

Term of patent 14 years

Int. Cl. D2—04

U.S. Cl. D2—334

FIG. 3

FIG. 2

FIG. 1

FIG. 1 is a side elevational view of a sock showing my new design, the opposite side being a mirror image of that shown;

FIG. 2 is an enlarged view of the area shown in block 2 of FIG. 1; and

FIG. 3 is an enlarged view of the area shown in block 3 of FIG. 2.

The opposite side of FIG. 1 of the sock is the same as the side shown in FIG. 1.

I claim:

The ornamental design for a sock, as shown and described.
